UNITED STATES PATENT OFFICE

GEORGE A. SAVILLE, JR., OF LINCOLN, NEBRASKA

ADJUSTABLE WASTE RECEIVER

Application filed February 20, 1932. Serial No. 594,371.

My invention relates to waste receivers for catching the shavings and other waste when boring the cylinders of internal combustion engines.

The primary object of the invention is the provision of a waste receiver which may be inserted from the top of the cylinder and seated beneath the cylinder where it remains in operative position until the job is completed, the waste receiver being then removable through the cylinder.

Another of my objects is the provision of a waste receiver which is collapsible to a size where it may be passed through the cylinder, the receiver being also expansible to seat underneath the cylinder in such a way that it will catch all of the shavings and other waste when grinding or boring the cylinder.

More specifically, my object is to provide a waste receiver which may be expanded and contracted by means of ribs which act much like those of umbrellas and parasols.

Another of my objects is the provision of a waste receiver in cup form having its abutments on the crank shaft beneath the cylinder and having a spring for forcing the receiver into intimate contact with the bottom surface of the cylinder block.

Another object of my invention is the provision of a special tool for inserting and removing the waste receiver.

Having in view these objects and others which will be pointed out in the following description, I will now refer to the drawing, in which

Figure 1 is a sectional view of my waste receiver seated in position on the crank shaft with the mouth of the receiver in intimate contact with the cylinder block and underneath one of the cylinders.

Figure 2 is a view in perspective of the waste receiver.

Figure 3 is a view in perspective of the tool employed for inserting and removing the waste receiver from the cylinder, a small portion of the operating mechanism of the waste receiver being also shown.

The waste receiver itself is shown at 10. This is cup-shaped and it may be made from rubber, rubber composition, leather, fabric or

any other similar material which is collapsible. The receiver 10 is reinforced by means of a number of ribs 11 which are preferably made of a flat and slightly resilient material. These ribs extend lengthwise of the receiver and they are turned inwardly into radial position to cover the bottom of the receiver. The receiver is also provided with a central aperture in its bottom, the receiver being reinforced at this point by means of a collar 12. A hollow spindle 13 extends through the central aperture, the ribs 11 being turned up between the sleeve 12 and the spindle 13 which are all secured together. Surrounding the lower extremity of the spindle 13 is a coil spring 14 having secured to the lower extremity thereof a fork 15 which is adapted to seat on the crank shaft 16 of the engine. The concave surface of the fork is preferably provided with a cushioning material at 17 to prevent abrasion or other injury to the smooth surface of the crank shaft. It is evident from the foregoing description that the receiver 10 may be positioned beneath the walls 18 of the cylinder and that the pressure of the spring 14 will hold the upper edge of the receptacle in intimate contact with the bottom of the cylinder block.

The ribs 11 terminate at their upper ends a little below the upper edge of the cup. In this manner the metallic parts of the cup will not contact directly with the cylinder block, the cup material being slightly overlapped to form a gasket for the cylinder block. The cup 10 may also be reinforced at its upper extremity by means of any expansible member 19 such as a coil spring or rubber band.

The ribs 11 are braced by means of braces 20 which are pivotally secured to the individual ribs 11 and to a collar 21. The collar 21 is slideable on the spindle 13. The upper end portion of the spindle 13 is externally threaded for the reception of a nut 22. The slideable collar 21 has an internal circular rib which seats in a groove of the nut 22. It is evident that the turning of the nut 22 will cause the collar 21 to move up or down to thus either expand or contract the mouth of the receptacle. The nut 22 is provided with a wrench engaging member 23.

For lifting the cup out through the cylinder after its mouth has been contracted, the spindle 13 is so formed that it may be engaged by a hook. As previously described, the spindle 13 is hollow. The opposite walls of the spindle are provided with bayonet slots 24 which are adapted to receive a hook. The hollow portion of the spindle has a plunger 25 therein which is spring pressed by means of a coil spring 26 having its upper end bearing against the plunger 25 and its lower end bearing against an abutment 27 inside the spindle 13. The hook which engages the bayonet slots 24 must therefore be so formed that it will press the plunger 25 downwardly to permit its insertion into the hollow spindle 13. The plunger 25 closes the mouth of the bore of the spindle 13 to prevent the entrance of waste.

The tool employed with the cup is best shown in Figure 3, parts being also shown in Figure 1. The rod 28 passes through a sleeve 29 which is knurled at 30. The rod 28 has a handle 31 of any convenient form and it is provided with a pin 32 passing through the rod 28 and projecting from opposite sides thereof. The diameter of the rod 28 is substantially that of the plunger 25. Pressure on the rod 28 will force down the plunger 25 so that a slight turn of the rod 28 will seat the pin 32 in the bayonet slots 24. The pin 32 also functions to keep the two parts in assembled relation so that the sleeve 29 can not slide off the rod 28 even though it is slidable thereon for a considerable distance. If it is desired to use the tool to expand or contract the mouth of the receiver, the sleeve 29 is pushed down its full distance on the rod 28 so that its wrench socket 33 may be forced into engagement with the nut head 23. The tool shown in Figure 3 may thus be used either for expanding or contracting the mouth of the receiver or it may be used to pull the receiver with its contents out through the top of the cylinder.

Having thus described my invention in such full, clear, and exact terms that its construction and operation will be readily understood by others skilled in the art to which it pertains, what I claim as new and desire to secure by Letters Patent of the United States is:

1. A waste receiver for use beneath an engine cylinder which is open at the top and bottom, said waste receiver having an expandable mouth which is contractible for insertion through the cylinder from the top thereof.

2. A waste receiver for use beneath an engine cylinder which is open at the top and bottom, said waste receiver having a rigid bottom of a diameter less than that of the cylinder and having an open expandable and contractible top, said top having a diameter less than that of the cylinder when con-

tracted and greater than that of the cylinder when expanded.

3. A waste receiver for use beneath an engine cylinder which is open at the top and bottom, said waste receiver having an expandable mouth which is contractible for insertion through the cylinder from the top thereof, and means for seating said waste receiver with its expanded mouth pressed tightly against the under side of the cylinder block. 75

4. A waste receiver for use beneath an engine cylinder which is open at the top and bottom, said waste receiver having an expandable mouth which is contractible for insertion through the cylinder from the top thereof, means for manually expanding and contracting said mouth, and means for seating said waste receiver with its expanded mouth pressed tightly against the under side 85 of the cylinder block. 80

5. A waste receiver for use beneath an engine cylinder which is open at the top and bottom, said waste receiver having an expandable mouth which is contractible for insertion through the cylinder from the top thereof, ribs for the side of said receiver, the upper extremities of said ribs being movable toward or away from the center line of said receiver for contracting or expanding said mouth, and means for seating said waste receiver with its expanded mouth pressed tightly against the under side of the cylinder block. 90 95

6. A waste receiver for use beneath an engine cylinder which is open at the top and bottom, said waste receiver having a rigid bottom of a diameter less than that of the cylinder and having an open expandable and contractible top, said top when contracted having a diameter less than that of the cylinder and greater when expanded than that of the cylinder, and means for seating said receiver with its open top pressed tightly 105 against the under side of the cylinder block. 110

In testimony whereof I affix my signature.
